UNITED STATES PATENT OFFICE.

WILLIAM L. COPLEY, OF NEWCASTLE, INDIANA.

DESIGN FOR A TIRE TREAD.

Application filed August 21, 1922. Serial No. 3,480. Term of patent 3½ years.

To all whom it may concern:

Be it known that I, WILLIAM L. COPLEY, a citizen of the United States, residing at Newcastle, in the county of Henry and State of Indiana, have invented a new, original, and ornamental Design for Tire Treads, of which the following is a specification, reference being had to the accompanying drawings, forming a part thereof.

In the drawings:

Figure 1 is a top plan view of a portion of the tire tread.

Figure 2 is a cross-section on the line 2—2 of Figure 1.

I claim:

The ornamental design for a tire tread, as shown.

WILLIAM L. COPLEY.
